UNITED STATES PATENT OFFICE.

WILLIAM FREDERICK MANGELS, OF NEW YORK, N. Y.

AMUSEMENT APPARATUS.

1,128,890.

Specification of Letters Patent. Patented Feb. 16, 1915.

Application filed June 26, 1914. Serial No. 847,365.

To all whom it may concern:

Be it known that I, WILLIAM F. MANGELS, a citizen of the United States, and a resident of the city of New York, Coney Island, borough of Brooklyn, in the county of Kings and State of New York, have invented a new and Improved Amusement Apparatus, of which the following is a full, clear, and exact description.

10 This invention relates to an amusement device adapted for popular resorts and is of that type in which passengers ride in a car which has a predetermined motion tending to produce amusement and merriment for 15 the occupants and spectators.

The invention has for its general objects to provide a novel amusement apparatus which is of comparatively simple construction, occupies relatively little space and is 20 thoroughly reliable and safe in operation.

Another object of the invention is the provision of a track along which the passenger cars travel, the track having alternate straight portions and turns, curves or 25 corners, in combination with a car-driving means, such as an endless chain, to which the cars are independently connected, so that each car will trail along the straight portions of the track and acquire a quick centrifugal motion in passing around the 30 curves, turns or corners, the suddenness of which causes agitation or commotion of the occupants, and hence much merriment and amusement, and as the car passes the turn, 35 curve or corner it will again take up a trailing position until another turn, curve or corner is encountered, so that broadly the invention contemplates an endless chain or other traveler having a constant speed of 40 travel and one or more cars connected therewith in such a manner that each car will have a trailing motion followed by a quick, outward centrifugal swing succeeded by another relatively slow trailing motion, and 45 so on until the apparatus is brought to a stop.

Another object of the invention is the provision of a simple, effective and novel attaching means between the endless chain 50 or driver and the cars, whereby the cars are cushioned in passing through a cycle from a trailing position through an outward swinging centrifugal position and back again to trailing position, so that over-travel

of the car during the outward centrifugal swing will be prevented and smooth running of the apparatus insured.

Another object of the invention is the provision of an endless chain having outstanding arms, to the outer ends of which a car is attached so that, as an arm on the chain passes around a curve, turn or corner, the outer end of the arm will travel at a greater rate of speed than the inner end to thereby cause a centrifugal action of the car in passing a curve, turn or corner.

An additional object is to provide connecting means between each car and its associated arm on the driving chain, such means including a swinging tongue or link connected with the arm and a brace connected with the rear portion of the tongue and slidably connected with the arm, and said car being pivotally connected with the tongue and having yielding means for allowing of a limited swinging movement of the car on the tongue in the movement of the car passing through a cycle of movements as the car passes around a curve, turn or corner of the track.

The invention has as a further object the provision of a modified form of the invention wherein the floor on which the car is moved is provided with an endless slot through which studs extend upwardly from a driving means under the floor, and to the studs are connected passenger cars, which in finishing an evolution in passing around a turn, curve or corner, make and describe, due to the momentum acquired, a loop before again assuming a trailing position.

With such objects in view, and others which will appear as the description proceeds, the invention comprises various novel features of construction and arrangement of parts which will be set forth with particularity in the following description and claims appended hereto.

In the accompanying drawings, which illustrate certain embodiments of the invention, and wherein similar characters of reference indicate corresponding parts in all the views, Figure 1 is a plan view of the complete amusement apparatus; Fig. 2 is an enlarged sectional view on the line 2—2, Fig. 1; Fig. 3 is a side view of one of the passenger cars; Fig. 4 is a plan view of the connecting means between one of the cars

and the driving chain; Fig. 5 is a sectional detail of a modified form of the invention, wherein the driving means is located under the floor and the latter is provided with an endless slot through which connection is made between the driving means and cars; Fig. 6 is a diagrammatic view of a modified form of guide means for the car driving chain; Figs. 7, 8 and 9 are further modifications of chain driving means; and Fig. 10 is a plan view of the modification of a complete floor embodying the construction shown in Fig. 5.

Referring to the drawings, and more particularly to Figs. 1 to 4 inclusive, A designates a horizontal floor that constitutes a course over which the passenger cars B are adapted to travel in passing around a central raised platform C. Extending around this raised platform is an endless chain D which constitutes the car-driving means, and at one end of the platform is a large sprocket wheel 1 which supplies the power to the chain, and at the opposite end is a guide wheel or idler 2. The vertical walls 3 of the platform serve to guide the portions of the chain between the wheels 1 and 2, and these walls slightly diverge from each wheel toward the center of the platform, so that the chain will run in contact with the walls and prevent lateral flapping as the chain is driven. Any suitable means may be employed for driving the chain, as, for instance, a rack 4, on Fig. 2, disposed under and connected with the sprocket wheel 1, and meshing with the circular rack 4 is a pinion 5 on a vertical shaft 6, which vertical shaft is connected by a bevel gearing 7 with a horizontal shaft 8 connected with a prime mover or other suitable source of power. The floor or course A may have stairs 9 to provide access to and from the car.

The cars B are of any desired construction and comprise a base or platform 10 which is provided with a pair of front casters 11 and a pair of rear casters 12 which are swiveled so as to permit a car to move freely in different directions on the floor or course A. Each car has a seat 13 for the passengers and a handle bar 14 shown in Figs. 2 and 4 is provided for the passengers to grasp so as to hold themselves as the car is thrown violently outwardly by centrifugal force, as in passing around curves, turns or bends in the course.

The means E for connecting each car with the driving chain D comprises a horizontally extending arm 15, a main forward brace 16, a trailing tongue or link 17, and a rear axle brace 18. The arm 15, shown in Fig. 4, has its inner end pivotally connected at 19 with the driving chain D, and on the outer end of the arm 15 is a head-piece 20 to which the brace 16 and tongue 17 are piv-

otally connected at 21 and 22, respectively, and inwardly of the head-piece 20 is a roller or wheel 23 which rides on the floor A and supports the arm and its associated parts 16, 17 and 18 off the said floor. On the forward part of the car platform 10 are a pair of plates 24, and between them extends the rear end of the brace 18, which rear end is connected to the plates 24 by a bolt or king-pin 25. This king pin passes through the link or tongue 17 so as to connect the latter with the car, but the tongue extends rearwardly beyond the king-pin or bolt 25, and its rear end 26 is connected with the forward end of a stiff helical extension spring 27 which has its rear end adjustably connected by a bolt or the like 28 with a bracket 29 on the bottom of the car, said spring extending longitudinally of the car and serving to hold the same centralized with respect to the tongue 17, but allowing the car to swing through a limited arc about the king-bolt 25 as a center, which swinging movement is indicated by the dot and dash line position *a*, Fig. 4, and the broken line position *c*. The front end of the brace 18 is pivotally connected at 30 with a collar 31 slidable on the arm 15, and this collar is movable into engagement with spring abutments 32 and 33 arranged on the inner and outer ends of the arm 15 for yieldingly limiting the movement of the car inwardly toward the chain from normal position, or outwardly from such position.

In operation the cars B when traveling along the relatively straight sides of the platform C are carried along in a trailing relation to the driving chain or with the cars disposed centrally behind the outer ends of the arms 15. When, however, each arm begins to pass around the wheel 1 or 2, the outer end of the arm moves at an accelerated speed, whereas the inner end continues to move at its normal rate, and by reason of this centrifugal force is brought into play, which causes the car to swing with considerable power outwardly about the pivotal connection 22 between the arm 15 and the tongue 17, and in this movement the collar 31 of the brace 18 slides outwardly and presses the spring 33, which, by its increasing tension, will cushion the movement produced by the centrifugal force. When the tongue 17 swings outwardly to its limit, the car, by reason of its momentum, will swing on the king-bolt 25 as a center, whereby the spring 27 is placed under tension, which will eventually react and bring the car back to centralized position with respect to the tongue. As the car continues to make a sweep around the wheel 1 or 2, the arm 15 will finally assume a position where its outer end will travel at the same rate of speed as the inner end, and the spring 33, together with the trailing action of the car, 130

will move the car centripetally or toward the chain, and during this movement the collar 31 of the bracket 18 will slide inwardly on the arm 15, and the momentum of the inwardly-moving car will engage the collar 31 with the spring 32, which acts as a spring buffer to prevent shock as the car swings inwardly. As the arm 15 moves in a straight line from either wheel 1 or 2, the car, which has just gone through the centrifugal and centripetal movements, will automatically return to a trailing position, with the longitudinal axis of the car directly behind the outer end of the arm 15. This position will be maintained until the opposite end of the chain is reached, when the car will again go through a cycle of centrifugal and centripetal movements.

In the modification shown in Fig. 6, an elliptical endless car driving chain is shown, but instead of having large wheels at the ends a number of small idlers 35 are employed, whereby the curves may be made on a greater radius. The chain is driven in any suitable manner, as, for instance, by a driving sprocket wheel 36 driven by suitable means 37 from a motor 38. In Fig. 7 the carriage driving chain D is so guided as to follow the course of an isosceles triangle, while in Fig. 8 it takes the form of an equilateral triangle, and in Fig. 9 the form of a rhombus, but it is to be understood that various other lines of travel may be employed. At the wheels d comparatively sharp angles are formed so that the cars will be thrown out with considerable centrifugal force as these corners or angles are passed in the transit of the cars.

In the modification shown in Figs. 5 and 10 the floor A' is provided with an endless slot 39, and upwardly through this slot extend studs 40. These studs 40 are connected with an endless chain 41 which runs in a channel 42 formed by oppositely-disposed channel-irons 43, and on each stud 40 are guide rollers 44 which engage the flanges 45 of the channel irons. These channel irons of course follow the contour of the slot 39 in the floor A'. The cars B' are connected by link bars 46 with the upper ends of the studs 40 in such a manner that the link bars can swing around the studs as centers. It will be observed that as the cars are connected with the driving chain simply by the studs and link bars without any restraining devices, such as are shown in the form of the invention first described, the cars are free to over-travel, as shown in Fig. 10, at the latter part of the centrifugal action, due to the cars passing around the curves at the ends of the course formed by the slot 39. As the car travels along the straight part of the course it will trail behind its stud 40 until the curve is encountered, when the momentum will cause the car to tend to con-

tinue its straight movement, and at this point centrifugal force comes into play to throw the car outwardly, and if the speed of travel is great enough the car will describe a loop, as shown by the broken lines, Fig. 70 10, before it again assumes a trailing position. The car is free to make a loop, as the portions of the floor at both sides of the slot are on a level, so that the car is free to travel back and forth across the slot without interference. Obviously, the course of the car can be varied by changing the shape of the slot, as may be found desirable.

From the foregoing description taken in connection with the accompanying drawings, the advantages of the construction and method of operation will be readily understood by those skilled in the art to which the invention appertains, and while I have described the device which I now consider 85 to be the best embodiment thereof, I desire to have it understood that the device shown is merely illustrative, and that such changes may be made when desired as are within the scope of the appended claims. 90

Having thus described my invention, I claim as new and desire to secure by Letters Patent:

1. An amusement device comprising a course having one or more turns, a driving 95 means extending along the course, and a car loosely connected with the driving means to travel in a trailing position in approaching and after passing the turn or turns and adapted to swing out centrifugally in moving around the turn or turns. 100

2. An amusement device of the class described, comprising a course having one or more curves connected by straight portions, a driving means extending along the course, 105 a passenger car, and means for connecting the car to the driving means to permit the car to trail along the straight portions of the course and to swing outwardly by centrifugal force in passing around a turn. 110

3. An amusement device comprising an endless course having a plurality of curves and approximately straight between adjacent curves, a driving means extending along the course, a plurality of cars, and links pivotally connected with the driving means and with the cars for permitting the cars to trail while traveling along the straight portions of the course and to swing outwardly as the cars pass around the first part of the 115 curve and inwardly as a car passes from the curve to a straight portion of the track. 120

4. An amusement device comprising an endless driving element having a plurality of curves, arms extending outwardly therefrom, a car associated with each arm, and means for loosely connecting each car with its associated arm. 125

5. An amusement device comprising a course having a plurality of turns with in- 130

termediate straight portions, a traveling driving means moving along the course, arms connected with and extending outwardly from the driving means, a wheel on each arm and traveling on the said course, a car associated with each arm, and a link connection between each arm and its associated car.

6. An amusement device comprising a 10 floor, an endless driving chain, cars movable over the floor, arms extending outwardly from the said chain, braces between the arms and chain for holding the arms outstanding, rollers on the outer ends of the 15 arms and bearing on the floor, and connections between the arms and cars for permitting the cars to swing outwardly and inwardly during their travel over the floor.

7. An amusement device comprising a 20 floor, an endless driving chain having a plurality of curves and relatively straight portions between adjacent curves, braced arms extending outwardly in a horizontal position from the chain, a link hingedly connected 25 with the outer end of each arm, a car pivotally connected with each link, and means for limiting the swinging movement of the link with respect to the arm.

8. An amusement device comprising a 30 floor, an endless driving chain having a plurality of curves and relatively straight portions between adjacent curves, braced arms extending outwardly in a horizontal position from the chain, a link hingedly connected 35 with the outer end of each arm, a car pivotally connected with each link, a brace connected with the link and slidably connected with the arm, and buffering devices carried by the arm for limiting the sliding movement 40 of the brace on the said arm as the car swings inwardly and outwardly.

9. An amusement device comprising a driving chain, a guide having one or more curves and on which the chain travels, pivoted arms connected with the chain and extending outwardly therefrom, braces pivotally connected with the outer ends of the arms and with the chain at points forwardly of the arms, a trailing tongue or link pivotally connected with the outer end of each arm, a car pivotally connected with each tongue, and means for limiting the pivotal movement of each tongue on its respective arm.

55 10. An amusement device comprising a driving chain, a guide having one or more curves and on which the chain travels, pivoted arms connected with the chain and extending outwardly therefrom, braces pivotally connected with the outer ends of the arms and with the chain at points forwardly of the arms, a trailing tongue or link pivotally connected with the outer end of each arm, a car pivotally connected with each 65 tongue, a collar on each arm, buffers on the

inner and outer ends of each arm and with which the collar thereof is adapted to engage, and a brace connected with the collar of each arm and with the associated tongue.

11. An amusement device comprising a 70 driving means which follows a path having alternate straight portions and intermediate curves, a member connected therewith and extending outwardly therefrom, whereby the outer end travels faster than the inner 75 end when passing a curve, a tongue pivotally connected with the outer end of the arm, a car pivotally connected with the tongue, and means for limiting the pivotal movement of the car with respect to its 80 tongue.

12. An amusement device comprising a driving means which follows a path having alternate straight portions and intermediate 85 curves, a member connected therewith and extending outwardly therefrom, whereby the outer end travels faster than the inner end when passing a curve, a tongue pivotally connected with the outer end of the arm, a car pivotally connected with the 90 tongue, and a spring connected with the car and with the tongue for limiting the pivotal movement of the car on the tongue.

13. An amusement device comprising a driving means which follows a path having 95 alternate straight portions and intermediate curves, a member connected therewith and extending outwardly therefrom, whereby the outer end travels faster than the inner end when passing a curve, a tongue pivotally connected with the outer end of the arm, a car pivotally connected with the tongue, 100 means for limiting the pivotal movement of the car with respect to its tongue, and means for limiting the swinging movement of the 105 tongue with respect to the said arm.

14. An amusement device comprising a driving means which follows a path having alternate straight portions and intermediate curves, a member connected therewith and 110 extending outwardly therefrom, whereby the outer end travels faster than the inner end when passing a curve, a tongue pivotally connected with the outer end of the arm, a car pivotally connected with the 115 tongue, a spring connected with the car and with the tongue for limiting the pivotal movement of the car on the tongue, and means for limiting the swinging movement of the tongue with respect to the said arm. 120

15. An amusement device comprising a driving means which follows a path having alternate straight portions and intermediate curves, a member connected therewith and extending outwardly therefrom, whereby 125 the outer end travels faster than the inner end when passing a curve, a car pivotally connected at its front to the tongue at a point intermediate the ends of the latter, and a helical extension spring having its 130

front end connected with the rear end of the tongue and its rear end connected with the car.

16. An amusement device comprising a driving means which follows a path having alternate straight portions and intermediate curves, a member connected therewith and extending outwardly therefrom, whereby the outer end travels faster than the inner end when passing a curve, a car pivotally connected at its front to the tongue at a point intermediate the ends of the latter, a helical extension spring having its front end connected with the rear end of the tongue and its rear end connected with the body, a brace connected with the tongue and movably connected with the arm, and buffering means for limiting the movement of the brace on the said arm.

20 17. An amusement device comprising a floor having a slot therein formed with spaced curved portions connected by straight

portions, means traveling along the slot, and a car rolling over the floor and connected with the said means, whereby the car trails 25 as the means travels along the straight portion of the slot and acquires a centrifugal or centripetal movement in traveling along a curved portion of the slot.

18. An amusement device comprising a 30 floor having an endless slot provided with a plurality of turns and straight portions between the turns, an endless chain under the floor, studs connected with the chain and extending upwardly through the slot, 35 cars adapted to roll over the floor, and a link connecting each car with a stud.

In testimony whereof I have signed my name to this specification in the presence of two subscribing witnesses.

WILLIAM FREDERICK MANGEL.
